UNITED STATES PATENT OFFICE.

WILLIAM HAECKEL, OF NEW YORK, N. Y.

UMBRELLA-FRAME.

No. 838,984.

Specification of Letters Patent.

Patented Dec. 18, 1906.

Application filed October 8, 1906. Serial No. 337,944.

To all whom it may concern:

Be it known that I, WILLIAM HAECKEL, a citizen of the United States, and a resident of the city of New York, borough of Brooklyn, 5 in the county of Kings and State of New York, have invented a new and Improved Umbrella-Frame, of which the following is a full, clear, and exact description.

This invention has for its object to provide 10 means adapted to enable an umbrella rib and stretcher connected therewith to be readily detached from an umbrella-frame and replaced when desired. This I accomplish by 15 the means illustrated in the accompanying drawings, in which drawings like characters of reference indicate like parts throughout the views, and in which—

Figure 1 is a side elevation, partly in section, of my invention applied to the parts of 20 an umbrella-frame. Fig. 2 is a perspective view of the upper end of a rib provided with a head. Fig. 3 is a perspective view of the lower end of a stretcher attached to a swivel-coupling; and Fig. 4 is a vertical transverse 25 section, enlarged, of the swivel-coupling shown in Fig. 3.

As illustrated in the drawings, 1 represents an umbrella-rod of ordinary construction, having a runner 2 mounted thereon and connected by means of a swivel-coupling with stretchers 4. The stretchers 4 are pivotally connected, by means of pivot-pins 4^a, with lugs 5, fixedly secured to ribs 6. The ribs 6 have a threaded engagement at one end with 35 heads 7, which are pivotally secured, by means of pivot-pins or a wire 7^a, with a crown 8, fixedly secured to the umbrella-rod. A swivel-coupling 3 secures the inner ends of the stretchers 4 to the runner 2 and comprises a sleeve having an interior thread engaging a corresponding thread formed on the 40 end of the stretcher 4 and a swivel connection comprising a stud 3^a, connected with a head 3^b, preferably by means of a threaded engagement. The head 3^b is hinged to the 45 runner 2 by means of a wire 3^c, passing through a plurality of members attached

thereby to said runner. By means of such construction the inner end of the stretcher 4 may be readily unscrewed and detached from 50 the sleeve 3 of the swivel-coupling, and when the stretcher is released from said coupling the upper end of the rib 6 may be readily unscrewed and detached from the head 7, which is pivotally connected to the crown 8, and by 55 reversing the order of such operation a new rib and stretcher may be readily secured to the crown and runner of the umbrella-frame.

Having thus described my invention, what I claim as new, and desire to secure by Letters Patent, is—

1. The combination with an umbrella-rod, of a crown fixedly secured thereto, a runner mounted on said rod, a rib provided with a head detachably secured thereto, and hinged 65 to said crown, a stretcher pivotally attached to said rib, and a swivel-coupling connecting said stretcher and runner, substantially as shown and described.

2. The combination with an umbrella-rib, 70 of a head detachably secured thereto by means of a threaded connection, a stretcher pivoted to said rib, and a swivel-coupling detachably secured to said stretcher, substantially as shown and described.

3. The combination with an umbrella-rod, 75 of a crown fixedly secured thereto, a runner mounted on said rod, a rib provided with a head detachably secured thereto and pivotally connected with said crown, a stretcher 80 pivoted to said rib, and a swivel-coupling connecting said stretcher and runner, comprising a sleeve having a threaded engagement with said stretcher, a head hinged to said runner, and a pivotal connection between said sleeve and head, substantially as 85 shown and described.

In testimony whereof I have signed my name to this specification in the presence of two subscribing witnesses.

WILLIAM HAECKEL.
